CLAIM

The ornamental design for a push stick for a saw table or the like, substantially as shown and described.

DESCRIPTION

FIG. 1 is a perspective view of a push stick for a saw table or the like showing my new design;

FIG. 2 is a rear view thereof;

FIG. 3 is a front view thereof;

FIG. 4 is a bottom view thereof;

FIG. 5 is a side view thereof, the opposite side being identical thereto;

FIG. 6 is a top view thereof; and

FIG. 7 is a cross section thereof taken at line 7—7 of FIG. 6.
